METHOD AND APPARATUS FOR FORMING
METALLIC RECEPTACLES

James K. Matter, La Grange, Ill., and Gustave J. Horak, New Kensington, Pa., assignors to The Aluminum Cooking Utensil Company, New Kensington, Pa., a corporation of Pennsylvania

Application December 28, 1935, Serial No. 56,464

8 Claims. (Cl. 113—52)

This invention relates to an apparatus for and method of making metallic receptacles, and while the invention can be applied to making metallic receptacles of various kinds, it is particularly adapted to making metallic receptacles having a thick bottom and top edge and a relatively thin, smooth side wall by drawing and spinning heavy gauge metal.

An object of this invention is to provide an improved apparatus for forming metallic receptacle having a thick bottom and top edge and a side wall of varying thickness.

A further object of the invention is to provide a method by which a metallic receptacle having a thick bottom and top edge, a relatively thin side wall and an integral supporting chime around its bottom may be drawn and spun.

A further object of this invention is to provide a process by which a metallic receptacle having a thick bottom and top edge and a smooth, relatively thin side wall can be completely formed by a single spinning operation.

The invention has for further objects such other operative advantages and results as are found in the apparatus and method described and claimed herewith.

The present invention will be described in connection with selected illustrative embodiments thereof in apparatus shown in the accompanying drawings, wherein:

Fig. 1 is a plan view of the spinning machine proper showing the work in section;

Fig. 2 is an end elevational view partially in section;

Fig. 3 is a view similar to Fig. 1, but showing a modified form of the invention;

Figs. 4, 5, 7 and 9 are views partially in section showing various receptacles formed in accordance with the invention;

Fig. 6 is a view partially in section similar to Fig. 3 but illustrating a later stage of the operation;

Fig. 8 is a view partially in section showing the drawn blank from which a receptacle is to be formed by spinning.

Referring to Figs. 1 and 2 of the drawings, it will be seen that the machine is supported upon the general frame-work 1 of a lathe of conventional construction, a portion of which, including legs 2 and parallel side frame members 3, is shown in the drawings. The side frame members 3 are provided with guides 4 upon which a tool carriage 5 is mounted for longitudinal reciprocal movement. Spinning rolls 6 are rotatively mounted on the roll supporting slides 7, which

are in turn mounted so as to be transversely movable along the guides 5 of the carriage 5.

The carriage 5 may be reciprocated on the guides 4 by any suitable mechanism such as, for instance, that shown in which screw shafts 9 are employed. The screw shafts 9 are arranged to engage screw threaded apertures in the carriage 5 and may be driven in any convenient manner.

The spinning rolls 6 are preferably tapered over a greater portion of their length as shown 10 at 15, the tapered portion being utilized in spinning the heavy gauge metal to form the side wall of the receptacle. At one end of these rolls, the tapered portion 15 joins a cylindrical portion 16 which in use smooths out the surface of the side 15 wall of the receptacle. The rolls 6 are preferably so arranged that one roll will slightly lead the other during the formation of the receptacle.

The spinning rolls are fed into and away from the work by any suitable mechanism such as the one shown in Fig. 2 of the drawings, for example. Here nuts 17 are secured to the roll supporting slides 7 by screws 18. The feed screw 19, extending across the machine and provided at one end with a right-hand screw thread, and at the other 25 with a left-hand screw thread, is arranged in similar screw-threaded apertures in the members 17. A hand wheel 20 upon one end of the feed screw 19 serves as a means for turning the screw and causing the roll supporting slides 7 and the rolls 6 to move toward, and recede from each other as desired.

The drawn blank 21 from which the finished receptacle is made is shown in Fig. 8 of the drawings. During the spinning operation this blank 35 is supported upon a mandrel 22. The mandrel 22 is mounted at one end upon a chuck 23 and is secured thereto by bolts 24, arranged in T-shaped slots 25 formed in the face of the chuck. At the opposite end the blank is held on the 40 mandrel by a tailstock 26.

The operation of the mechanism shown in Figs. 1 and 2 will now be described. The blank 21 which has been formed from a sheet of rather heavy gauge metal by a drawing operation or in other suitable manner is placed upon the mandrel 22. The mandrel 22 is rotated and the rolls 6 are fed into the blank 21 by rotating the hand-wheel 20. The carriage 5, upon which are mounted the roll-supporting slides 7, is fed along the lathe bed 3 and the spinning rolls 6 act to spin out the central portion of the side wall of the receptacle, leaving the bottom of the receptacle and its upper edge the original thickness of the blank 21. At the beginning of the movement of 55

the rolls 6 along the blank 21, their tapered portions 15 spin out the side wall. Thereafter the adjoining cylindrical portions 16 smooth the portions of the wall just previously spun by the tapered portions 15. To produce the finished receptacle 27 with a rim 28 the spinning rolls are backed away from the receptacle at a point some distance from the top edge of the receptacle.

Obviously, by the method just described, it is possible to form a finished metallic receptacle having a thick bottom and top edge and a smooth relatively thin side wall by a single spinning operation.

It will be evident that the apparatus described need be altered only slightly to produce various shapes of metallic receptacles. If a receptacle similar to the one 29 shown in Fig. 5 is desired which has, in addition to a thick bottom and top edge and a relatively thin side wall, an integral supporting head or chime 30 around its bottom, rolls 31 similar to those shown in Fig. 3 of the drawings should be employed. The rolls 31 are formed with a cylindrical portion 32 at one end, an adjoining tapered central portion 33 and an adjoining cylindrical portion 34 at the other end. If preferred, the rolls 31 may be rounded slightly at either or both ends.

To aid in forming, around the receptacle bottom, the integral supporting chime 30, it is preferable that a tailstock 35 of the type shown in Figs. 3 and 6 of the drawings be provided. This tailstock is preferably formed with a tapered portion 36.

In the operation of this embodiment of the invention, the thin side wall of the receptacles are formed in much the same manner as that described hereinabove except that the spinning operation is begun at a point slightly higher along the side of the blank 21. After the side wall and the top rim of the receptacle have been formed, the rolls 31 are fed along the screw shafts 9 in a reverse direction until the lower portions 32 of the spinning rolls come into contact with the excess of metal 28' remaining at the bottom of the unfinished receptacle. This causes the excess metal to flow in the opposite direction from the flow of metal during the formation of the side wall, thereby producing the integral supporting chime 30 shown on the receptacle 29.

Receptacles made by the process and apparatus embodied in the present invention may, of course, be formed in any suitable size or shape. A few such receptacles are shown in the drawings. In each instance the manufacture of these receptacles is essentially the same, that is, a cup-shaped blank of heavy gauge metal is spun out so that a metallic receptacle having a thin side wall and a relatively thick bottom and top edge is formed. The design of the top edge may be varied, of course, by changing the design of the rolls used to perform the spinning operation.

As pointed out hereinabove, the receptacle 27 may be readily formed by utilizing the apparatus shown in Figs. 1 and 2, while the receptacle 29 with its chime 30 may be manufactured by the embodiment of the invention shown in Figs. 3 and 6 of the drawings. The receptacle 37 shown in Fig. 9 is formed in much the same manner as the receptacle 29, with the exception that its integral chime 38 is exteriorly tapered by utilizing during the reverse spinning operation the tapered portion 33 of the rolls 31. The chime 39 shown on the receptacle 46 in Fig. 4 may be formed by using the rolls 31 so that the portion 32 of the rolls is adjacent the upper boss and then per-

forming the customary back spinning operation on the excess of metal left at the bottom of the drawn blank.

From the above, it will be seen that improved apparatus and a practical method are provided for forming, from a drawn blank, a metallic receptacle having a thick bottom and top edge and a smooth, relatively thin side wall by a single spinning operation. Furthermore, it will be seen that a practical means has been provided for forming an integral supporting chime about the base of a metallic receptacle.

It will be understood, of course, that while this invention has been described with reference to certain preferred embodiments thereof, various modifications and changes may be made therein within the spirit of the invention, as set forth in the appended claims.

We claim:

1. A method of forming a metallic receptacle, which method comprises providing a cup-shaped blank having a bottom and side wall of relatively heavy gauge, spinning the central portion of said side wall to cause the metal therein to flow in the direction of the open end of said blank, and subsequently forming a chime around said bottom by spinning the lower edge of said side wall past said bottom in a reverse direction.

2. A method of forming a metallic receptacle, which method comprises providing a cup-shaped blank having a bottom and side wall of relatively heavy gauge, spinning the central portion of said side wall to cause the metal therein to flow in the direction of the open end of said blank, and subsequently spinning the lower portion of said side wall past said bottom to form a support for said receptacle.

3. The method of forming a metallic receptacle which comprises providing a cup-shaped blank having a bottom and side wall of relatively heavy gauge, spinning said side wall from a point above said bottom by spinning means to cause a metal flow in the direction of the open end of said blank and simultaneously smoothing the surface thereof, and subsequently forming a bead around said bottom by spinning the lower edge of said side wall from a point above said bottom in a reverse direction.

4. The method of forming a metallic receptacle which comprises providing a cup-shaped blank having a bottom and side wall of relatively heavy gauge, spinning the central portion of said side wall by spinning means to cause a metal flow in the direction of the open end of said blank, simultaneously smoothing the surface thereof, and subsequently spinning the lower portion of said side wall past said bottom to form a support for said receptacle.

5. The method of forming a metallic receptacle which comprises providing a cup-shaped blank having a bottom and side wall of relatively heavy gauge, spinning said side wall from a point above the bottom of the receptacle to cause a metal flow in the direction of the open end of said blank, and forming a chime around said bottom by spinning the lower edge of said side wall in a reverse direction.

6. The method of forming a metallic receptacle which comprises providing a cup-shaped blank having a bottom and side wall of relatively heavy gauge, spinning said side wall from a point above the bottom of the receptacle to cause a metal flow in the direction of the open end of said blank, simultaneously smoothing out said side wall, and forming a chime around said bottom by spinning

the lower edge of said side wall in a reverse direction.

7. Apparatus for forming a metallic receptacle from a cup-shaped metal blank having a bottom and side wall of relatively heavy gauge, comprising in combination a rotary mandrel for supporting said blank, a plurality of reducing rolls movable along said mandrel in contact with said blank, said reducing rolls having their axes parallel with the axis of rotation of said mandrel and being tapered over a greater portion of their length and cylindrical for the remainder thereof, common adjusting means to move said rolls to radially fixed positions with respect to said mandrel and means to move said rolls along said mandrel, whereby the side wall of said blank is elongated and reduced in thickness by the tapered portions of said rolls and simultaneously smoothed by the cylindrical portions of said rolls.
8. Apparatus for forming a metallic receptacle from a cup-shaped metal blank having a bottom and side wall of relatively heavy gauge, comprising

ing in combination a rotary mandrel for interiorly supporting said blank, a tail stock adapted to engage the bottom of said blank, a plurality of reducing rolls movable along said mandrel having their axes parallel with the axis of rotation of said mandrel and having a cylindrical portion at each end joined by a tapered portion, adjusting means to move said rolls to radially fixed positions with respect to said mandrel and means to move said rolls along said mandrel in both directions, whereby the side wall of said blank is elongated and reduced in thickness by the tapered portions of said rolls and simultaneously smoothed by the cylindrical portions, and adapted by moving in a reverse direction to form a chime around said bottom of said blank, the interior configuration of said chime being controlled by the shape of the tail stock engaging said bottom portion.
